United States Patent Office

Des. 190,138
Patented Apr. 18, 1961

190,138

CLAMP

William Noga and John T. Chase, Van Nuys, Calif., as-
signors to Lockheed Aircraft Corporation, Burbank,
Calif.

Filed May 10, 1956, Ser. No. 41,444

Term of patent 14 years

(Cl. D54—13)

FIG. 3

FIG. 4

Figure 1 is a perspective view showing the top, front and one side of a clamp embodying our new design;

Figure 2 is a side elevation view thereof;

Figure 3 is a front elevation view thereof; and

Figure 4 is a bottom plan view thereof.

We claim:

The ornamental design for a clamp, as shown.
